United States Patent Office

Des. 176,768
Patented Jan. 31, 1956

176,768

ELECTRIC BEVERAGE DISPENSER

Clare E. Hodgman, Mamaroneck, N. Y., assignor to The Coca-Cola Company, New York, N. Y., a corporation of Delaware

Application June 21, 1955, Serial No. 36,614

Term of patent 14 years

(Cl. D2—3)

FIG. 1.

FIG. 2.

Fig. 1 is a view in perspective showing the front and one side of an electric beverage dispenser embodying my new design; and

Fig. 2 is a view in perspective showing the rear and other side thereof.

I claim:

The ornamental design for an electric beverage dispenser, as shown.
